UNITED STATES PATENT OFFICE.

FRANCIS A. NOLAN, OF ST. PAUL, MINNESOTA.

PHONOGRAPH-STOP.

1,335,911.

Specification of Letters Patent.

Patented Apr. 6, 1920.

Application filed October 13, 1917. Serial No. 196,382.

To all whom it may concern:

Be it known that I, FRANCIS A. NOLAN, a citizen of the United States, residing at St. Paul, in the county of Ramsey and State 5 of Minnesota, have invented a new and useful Improvement in Phonograph-Stops, of which the following is a specification.

This invention relates to improvements in stops for sound reproducing machines. 10 More particularly this invention relates to that class of stops which can be easily set for arresting the rotation of the record structure precisely at the end of the record being played. My invention contemplates certain 15 novel features pertaining to both the brake mechanism employed and the stop which is adapted to automatically release the brake and cause it to stop the machine.

With these and other objects in view, my 20 invention comprises the features of construction and combination of parts, which will hereinafter be more particularly described and claimed.

In the accompanying drawing forming 25 part of this specification, Figure 1 is a plan of a portion of a sound reproducing machine, to which my invention is shown applied part of the structure of said machine being broken away and in section; Fig. 2 is 30 a section taken on the line X—X of Fig. 1; Fig. 3 is a side elevation of an alternative construction of the trip or stop device, a detail of the sound record being shown; Fig. 4 is a plan of an alternative construc- 35 tion; Fig. 5 is a perspective of another alternative construction; Fig. 6 is a section of a detail of a sound tube showing the trip or stop illustrated in Fig. 5 applied thereto, and Fig. 7 is a section of an alter- 40 native construction, the position of the section being relative to the line X—X, Fig. 1.

In the drawing, A indicates a detail of 45 a sound reproducing machine of the disk type, having the usual turn table 2 and tone arm or sound tube 3, which is swiveled to turn in the usual manner as the sound box with its needle point or stylus follows the sound groove of the record on the turn table, either toward the center thereof or 50 outwardly toward its periphery. The turn

table 2 has the usual downwardly extending flange 4 on its periphery and arranged to engage the inner surface of this flange is the brake B, of trigger type, forming part of my invention. This brake has its brake 55 member 6 produced from a single piece of sheet metal or other suitable material having a tiltable brake shoe arm 7, pivoted by the screw 8 on the plate 9, which is secured to the top 10 of the sound reproducing machine by screws 11 or other suitable means.

Extending from the tiltable member 7 is an operating lever 12 by which the brake shoe member 6 can be tilted on its pivot. The extremity of the brake shoe arm 7 65 has a brake shoe or buffer element 13, which is arranged so that when the operating lever 12 is forced inwardly below the turn table, retarding action is applied against the inner surface of the flange 4 by the buffer 70 element 13, and when said lever 12 is shifted outwardly, the buffer element 13 is tilted out of contact with said flange and into connection with a catch or trigger 14, said catch 75 engaging the shoulder 15 on the brake element and serving to hold the brake element out of braking position. A coil spring 16 attached to an arm 17 on the brake element and to the catch 14 tends to releasably hold the brake element and catch 14 engaged. 80 The arm 12 is extensible by sections secured by screw 12' and slot 12'' connection for different adjustments.

The catch 14 is pivoted by the screw 17' on the plate 9 and carries a releasing arm 85 18 by the depression of which inwardly below the turn table, the hook 14 is disengaged from the shoulder 15 and the brake element released and set under the action of the spring 16. This brake is arranged on the 90 top of the sound reproducing machine in position, so that when the brake element is set, the buffer will engage the inner surface of the flange of the turn table and stop the machine, and when said brake element is engaged by the catch 14, it is released and held out of contact with said flange. A stop pin 20 carried by the plate 9 serves to limit the movement of the catch when the arm 18 is depressed. The outer free end of the arm 100

18 is provided with a shoulder 21 with the surface of which a stop C carried by the tone arm is adapted to press and automatically release the catch 14 and allow the 5 brake to engage and stop the turn table from revolving. The arm 12 performs the function of a hand setting device for the brake and the arm 18 the function of a release for setting said brake. The arm 18 is 10 also extensible by sections secured by screw 18' and slot 18'' connections for adjustment purposes.

The stop C is carried by a split ring 25, which is clamped rigidly around the vertical 15 portion of the tone arm, so that it will turn concentrically about the vertical axis of the tone arm as the latter swings during the operation of the machine when playing. This split ring carries a downwardly and 20 outwardly extending support 26, upon which a primary stop arm 27 is pivotally secured by the screw 28. This primary stop arm in turn carries a secondary stop arm 29, which is pivotally secured thereto by 25 the screw 30, the pivot motion of both the primary and secondary stop elements being horizontal. The secondary stop arm is arranged, so as to strike the shoulder 21 and cause the catch 14 to release the brake element 6 at a predetermined instant as the 30 tone arm moves horizontally when a record is being played. Before playing the record, the stop members are set in position on their pivots, so that the stop member 29 will 35 move into contact with the releasing member 18 when the stylus or other sound reproducing point reaches the end of the sound groove of the record being played. This is accomplished by first setting the 40 producing point at the end of the sound groove and then moving the stop arm 29 until it presses against the shoulder 21 when the brake element 6 is in set position, and then moving the tone arm into starting position and releasing the brake with the catch 45 14 in engagement with the shoulder 15, thus allowing the turn table to revolve freely.

In the operation just described, there is a predetermined distance which the brake 50 member 6 and arm 18 will travel from stopping position into cocked position of said brake member. This lost motion unless compensated by the trip renders the setting of the brake into braking position at precisely a 55 predetermined instant when the end of the sound groove is reached by the reproducing point inaccurate and imperfect. To overcome this imperfection and cause the brake to be set instantly when desired, I have provided the secondary stop member 29, which 60 plays freely on the pivot 30, it being guided in its movement by a pin 31 passing freely through a slot 32, which is arranged concentric to the pivot 30. The force required 65 to move the catch 14 out of engagement with

the shoulder 15 by depressing the releasing arm 18 is greater than the force required to swing the secondary stop member 29 upon its pivot 30, but the friction or binding tendency between the primary stop member 70 27 and the support 26 is arranged to be much greater than the force required to urge the releasing member 18 into releasing position and cause the setting of the brake.

Arranged in the end of an extension 33 on 75 the secondary stop member is an obstruction 34 in the form of an adjusting screw, the inner end of which is adapted to impinge or press against one side of the primary stop member, (see Fig. 2), so that when adjusting the primary stop member 27 by swinging the end of the secondary trip member in position against the shoulder 21 when the sound reproducing point is positioned at the end of the sound groove in the record 80 about to be played while the brake is in set position, the stop will subsequently set the brake precisely at the desired predetermined instant when the record is being played. When the playing of the record is started, 85 and the brake moved into released position, the lost motion of the releasing arm 18 caused by the movement of the brake into released position, or in other words the lost motion occurring between the reproducing point of the machine and the means for stopping the record moving element, is compensated by the subsequent free movement of the secondary stop member 29 when the latter comes into contact with the end of the 90 releasing member 18 until a side edge of the primary member 27 comes into contact with the shoulder 21, whereupon the brake is set. The end 35 of the slot 32 limits the backward movement of arm 29 and strikes the 95 pin 31, thus permitting the arm 27 to be moved back by arm 29 when desired. As a result my invention produces a stop for the brake, which will instantly release the brake without any lost motion when the sound reproducing point reaches substantially the exact place on the record at which it is desired that the machine shall cease playing. An opening 15' through plate 9 is provided 100 to admit a file for accurately filing the shoulders on members 6 and 14.

My invention may be variously modified within the spirit thereof for instance, the support 26 for the stop may be constructed as illustrated in Fig. 3 in which the arm 26' is attached by screws 26'' to the tone arm. The compensating stop may as illustrated in Fig. 4 be in the form of a disk 40 rotatably mounted upon the rigid support 41, which is adapted to be carried by the tone arm in 110 place of the primary and secondary stop members illustrated in Fig. 1. This disk has a segment thereof cut away, the depth of which below the outer peripheral surface 115 corresponding with the lost motion of the 120

- setting member 18 to be moved when releasing the brake into braking position. The disk in setting the device for operation is first turned, so that the outer peripheral surface 43 will press against the shoulder 21 when the sound reproducing point is placed at the end of the sound groove in the record being played. Subsequently when the record is started, the disk is turned so that 10 the outer peripheral surface 42 will contact with the shoulder 21 and cause the setting of the brake instantly when the sound reproducing point reaches the desired point in the sound groove of the record.
- 15 In the construction illustrated in Figs. 5 and 6, the holder for the trip instead of being a split ring as illustrated in Fig. 5 is constructed with a pair of spring arms 50 and 51, which removably clasp the 20 grooved ring 52 secured on the vertical portion of the tone arm. These arms 50 and 51 carry the depending outstanding support 53 upon which the single stop arm 54 is pivoted, by the screw 55. The arm 54 is 25 freely pivoted, that is the force required to move the releasing or trigger arm 18 is greater than the force required to swing the arm 54 on its pivot. The body of the arm 54 about the pivot 55 has a concentric recess 30 56 at the opposite ends of which are the shoulders 57 and 58. Carried by the support 53 are two stops, the one 59 being rigid and against which the shoulder 58 presses when the arm 54 is turned backwardly, and the other being adjustable and serving to limit the movement of the arm 54 in the opposite direction. The limited free movement thus allowed the arm 54 corresponds with the lost motion of the brake 40 release, above referred to. When setting the device to stop playing at a predetermined instant the clasp formed by arms 50 and 51 is turned into adjusted position by moving arms 54 toward and into contact with the 45 shoulder 21, when the brake is set. When the reproducing point approaches stopping position the arm 54 moves backwardly until shoulder 58 presses against pin 59, and the force required being greater to move said 50 clasp than to release catch 14, the arm 18 is depressed into releasing position and the brake is set.
- In Fig. 7 the primary arm 27 is shown constructed with a depending shoulder 60 and the secondary arm 29 formed with two flanges 61 and 62, the flange 61 serving to limit the swinging movement of the secondary arm in one direction and the flange 62 carrying an adjustable screw 63, the inner 60 end of which serves to press against the flange 60 to define the free movement afforded the secondary arms instead of the free movement limiting means set forth in Fig. 1. In this construction the slot 32 and 65 pin 31 are not used.
- It is obvious that by turning the devices over, so that the upper surfaces assume lowermost position and so that their parts move in an opposite direction, the invention will serve to automatically stop the machine 70 when the reproducing point travels outwardly instead of inwardly upon the record and reaches the outer end of the sound reproducing groove, such reversal of parts being within the scope of my invention. 75
- In accordance with the patent statutes, I have described the principles of operation of my invention, together with the apparatus which I now consider to represent the best embodiment thereof, but I desire to 80 have it understood that the construction shown is only illustrative, and that the invention can be carried out by other means and applied to uses other than those above set forth within the scope of the following 85 claims.
- Having described my invention, what I claim as new and desire to protect by Letters Patent is:—
1. Brake mechanism in which a brake 90 member occupies two positions, one where the brake is set and the other where the brake is released, a tone arm, having a support, an actuating member on the support, adjustable to cause the setting of the brake, 95 and means carried by the actuating member adapted to compensate for a predetermined amount of lost motion of said parts.
  2. Brake mechanism in which a brake 100 member occupies two positions, one where the brake is set and the other where the brake is released, a tone arm having a support adjustably secured thereto, an actuating member adjustable in said support 105 adapted to cause the setting of the brake; and means carried respectively by each of said brake and actuating members adapted to be selectively positioned to compensate for a predetermined amount of lost motion 110 of said parts.
  3. Brake mechanism in which a brake member occupies two positions, one where the brake is set and the other where the brake is released, a tone arm having a support adjustably secured thereto, an actuating member on the support adapted to cause the setting of the brake, and adjustable means carried respectively by each of said 115 brake and actuating members adapted to be adjusted to compensate for a predetermined amount of lost motion of said parts.
  4. Brake mechanism in which a brake member occupies two positions, one where the brake is set and the other where the brake 120 is released, a tone arm having a support mounted thereon, an actuating member mounted on said support and adjustable about the tone arm adapted to cause the setting of the brake, and means carried by the 125 130

actuating member adapted to be selectively positioned to compensate for a predetermined amount of lost motion of said parts.

5. Brake mechanism in which a brake member occupies two positions, one where the brake is set and the other where the brake is released, a tone arm having a support mounted thereon, an actuating member mounted on said support and adjustable

about the tone arm adapted to cause the setting of the brake, and means coöperating with said parts adapted to be selectively positioned to compensate for a predetermined amount of lost motion of said parts.

In testimony whereof I have signed my name to this specification.

FRANCIS A. NOLAN.
